UNITED STATES PATENT OFFICE.

WILLIAM J. TURNER, OF SAN FRANCISCO, CALIFORNIA.

SPRINKLER-HEAD.

1,292,664.

Specification of Letters Patent. Patented Jan. 28, 1919.

Application filed February 26, 1917. Serial No. 150,877.

To all whom it may concern:

Be it known that I, WILLIAM J. TURNER, a citizen of the United States, and a resident of the city and county of San Francisco, 5 State of California, have invented a new and useful Sprinkler-Head, of which the following is a specification.

My invention relates to automatic sprinkler heads.

10 An object of my invention is to provide a sprinkler head for automatically releasing a flow of water when the temperature in the vicinity passes a certain maximum.

Another object of my invention is to provide a sprinkler head in which the releasing structure is not rendered uncertain by corrosive action and disuse.

Another object of my invention is to provide a sprinkler head in which the melting 20 of the fusible bond, which normally prevents the collapse of the valve holding means, cannot be interrupted by the flow of water.

The invention possesses other features of advantage, some of which, with the foregoing, 25 will be set forth in the following description of the preferred form of my invention which is illustrated in the drawings accompanying and forming part of the specification. It is to be understood that I do not 30 limit myself to the showing made by the said drawings and description, as I may adopt variations of the preferred form within the scope of my invention as set forth in the claims.

35 Referring to the drawings:

Figure 1 is an elevation of the sprinkler head of my invention. The scale is large in order to show the details clearly. Portions are shown in section.

40 Fig. 2 is a sectional view taken on the line 2—2, of Fig. 1.

The sprinkler of my invention includes a nozzle 4 provided with two arms 5 and 6 and having a nipple 7 whereby the sprinkler head may be attached to the water supply pipe. At the opposite end of the head a deflector 9 of the usual form is secured by a screw 12 integral therewith which passes through a boss 13 carried by the arms 5 and 6 and terminates in a blunt, conical point 14 lying in the longitudinal axis A—B of the sprinkler head.

55 A valve cap 15 is seated upon the orifice of the nozzle 4 preferably with a gasket 17 of soft copper or comparable material arranged therebetween. The valve cap 15 is formed

with a curved top which terminates in a raised point 16 lying in the axial line A—B. The form of the cap prevents the catching and jamming of the releasing means at the moment of release.

Means are disposed between the two points 14 and 16 for retaining the cap 15 upon its seat under high water pressure and this means is arranged to collapse and drop out 65 of place to release the valve cap when the temperature in the vicinity of the head rises above a predetermined point.

The strut for holding the valve cap in place consists of three members. Two of 70 them are formed somewhat in the shape of an inverted V, and a locking member is disposed between them. One of these members 18—19 is provided with a conical depression in the end of the arm 18 fitting over the 75 point 16. The arm 19 is of spatulate form and extends nearly at right angles to arm 18. A ridge 21 is formed on the arm 18 adjacent the corner of the angle formed with the arm 19 for a purpose which will pres- 80 ently appear.

The other member 23—24 of the releasing strut is arranged upon the member 18—19. The arm 23 is provided at one end with a conical seat in which the point 14 engages. 85 The other end is given a rounded chisel point 25 and is seated in a similarly shaped seat or pocket formed in the arm 18 a small amount to the side of the axial line A—B. The arm 18 is wider at the seat than the 90 chisel point 25 and the seat terminates short of the edge of the arm so that transverse displacement of the chisel point from its seat is prevented. The arm 24 is integral with the arm 23 and extends outwardly to inclose, 95 with the arms 23 and 18, an open space c and then continues contiguous to the arm 19 for a short distance beyond the end of that arm. The arm 24 is also of spatulate form in that portion contiguous to the arm 19, so 100 that these two members form a broad surface contact with each other.

The space c may conveniently be triangular in form as shown in Fig. 1, but this shape is unessential. The important thing 105 is that there shall be an ample clearance between the members at this point.

As shown in Fig. 2, the arm 24 is wider than the arm 19 and extends out therefrom on each side. In the under side of the portion of the arm 24 which projects beyond the end of the arm 19 is formed a socket 26.

The locking member 28 lies contiguous to the under side of arm 19 and is bent near one end to form a head 29 which bears against the end of the arm 19 and seats in 5 the socket 26. A web of material is left on each side of the socket so that lateral displacement of the head is prevented.

It will be clear from the above and from an inspection of Fig. 1, that stress exerted 10 along the axial line A—B, such as will be effected by the water pressure tending to unseat the valve cap 15, will tend to rock the member 18—19 about the chisel point 25, accompanied by a separation of the contiguous surfaces of the arms 24 and 19. The member 18—19 becomes then a lever arm fulcrumed at 25, with a short lever arm stressed by the point 16 and a relatively long lever arm to resist movement and maintain 20 equilibrium in the frame. Pressure tending to separate the arms 19 and 24 also causes a pressure against the locking member 28 by the end of the arm 19 and this pressure tends to turn the locking member 25 in its socket 26, downwardly and away from the arm 19, thus releasing that arm from the arm 24.

The parts are normally held in the described relation and collapse prevented by 30 a fusible solder flowed between the contiguous surfaces of the arms 19 and 24 and the locking member 28. These surfaces are preferably tinned and the solder is flowed between them and banked up upon the flaring edges 24^a of the arm 24. A mass of solder 31 indicated by the dotted lines in Fig. 1, is also arranged within and upon the ridge 21 and extending over upon the end of the locking member 28 so that the solder 35 blocks the movement of the locking member past the ridge, just as the locking member blocks the movement of the arm 19 past the end of the arm 24. In addition to this blocking effect, or mechanical locking, of the parts, the solder forms a cohesive union 40 between them. The constituent parts of the solder are proportioned to give an alloy fusing at the desired temperature as for instance, 160° F.

50 The sprinkler head is assembled by soldering the members as explained and seating the strut upon the valve cap 15. The screw 12 is then tightened by turning the deflector 9 to hold the cap firmly against the water pressure. In case of fire in the vicinity of the sprinkler head, the solder between the flat surfaces of the members and then that in the locking block 31 is 55 fused, either by the direct contact with the flames or the rise in the temperature of the atmosphere above the fusing point of the solder. At the instant of fusing, the stress tending to separate the arms 19 and 24 causes them to fly apart, unseating the locking member 28 from its socket in the arm 24.

and throwing both strut 23 and arm 18 from the points 15 and 16 respectively and releasing the flow of water. It will be seen that with the structure shown, the complete collapse of the frame is assured immediately 70 following the melting of the solder. There is no possibility of a partial movement of the frame members sufficient to let some water pass, which, striking the solder, cools it so that further opening is prevented. The 75 collapse of the frame is practically simultaneous with the fusion of the solder and the arms have separated widely and beyond any possibility of attachment by cooled solder before the water touches them. The 80 separation of the members 23 and 18 by the space *c* is for the purpose of preventing adhesion of these surfaces by corrosion. When members lying close to each other are undisturbed for a long time, it is found that 85 corrosion frequently causes a union of the surfaces sufficient to destroy the sensitivity of the releasing mechanism. In applicant's device this is avoided by widely separating such parts. A further advantage in 90 the applicant's structure lies in the definiteness and difference in length of the lever arms which characteristic permits a close regulation of the temperature of release.

In order to discourage any attempt by the 95 user of the sprinkler head to reassemble the parts himself after the solder has once been melted, I drill a hole through the boss 13 and screw 12 after the frame has been first adjusted between the points 14 and 16, and 100 drive a pin 32 tightly therein, spreading the ends of the pin so that it cannot easily be removed.

I claim:

1. In an automatic sprinkler, a valve cap, 105 a lever bearing on said cap and extending outwardly therefrom at an angle with the axis of said sprinkler the outer portion of said lever being of spatulate form, a strut supported on the axial line of the sprinkler 110 at one of its ends and bearing at its other end on the lever to one side of the axial line, an arm extending from said strut and having a spatulate portion forming a surface contact with the spatulate portion of said lever, and with said strut and said lever enclosing an open space, and fusible means for uniting the spatulate portions of said strut arm and lever.

2. In an automatic sprinkler, a valve cap, 120 a lever bearing on said cap and extending outwardly therefrom at an acute angle with the axis of said sprinkler, the outer portion of said lever being of spatulate form, a strut supported on the axial line of the 125 sprinkler at one of its ends and bearing at its other end on the lever to one side of the axial line, an arm extending from said strut and having a spatulate portion forming a surface contact with the spatulate portion 131

of said lever and provided with a socket adjacent its end, a locking member of spatulate form seated in said socket and inclosing with said strut arm the end of said lever, and a fusible solder disposed between said locking member, lever and arm.

3. In an automatic sprinkler, a valve cap, a lever bearing on said cap and extending outwardly therefrom at an angle with the axis of said sprinkler, the outer portion of said lever being of spatulate form and bent at an angle to the inner portion, a strut supported on the axial line of the sprinkler at one of its ends and bearing at its other end on the lever to one side of the axial line, an arm integral with and extending from said strut and provided with a socket near its end and having a spatulate portion forming a surface contact with the spatulate portion

of said lever, a projection disposed upon the arm adjacent the bend therein, a locking member of spatulate form seated in said socket and forming a surface contact with the spatulate end of said lever, the end of the locking member being disposed adjacent the projection on said lever, and a fusible solder disposed between said locking member, lever and arm and about said projection and the end of said locking member to cohesively and mechanically secure the arm and lever together.

In testimony whereof, I have hereunto set my hand at San Francisco, California, this 19th day of February, 1917.

WILLIAM J. TURNER.

In presence of—
C. S. EVANS.
